His Attorney.

UNITED STATES PATENT OFFICE

2,311,425

DEHYDRATING COMPARTMENT

Albert F. Wild, Scotia, N. Y., assignor to General
Electric Company, a corporation of New York

Application June 10, 1942, Serial No. 446,430

9 Claims. (Cl. 62—89)

My invention relates to refrigerator cabinets and more particularly to dehydrating compartments or receptacles for use with refrigerator cabinets.

Certain foods as cereals and crackers, for example, are packaged to maintain the articles in a crisp condition. When the package is opened, moisture may be absorbed and the contents lose their crispness and become "stale."

Accordingly, it is an object of my invention to provide new and improved means in refrigerator cabinets and the like for maintaining food in a relatively dry condition and therefore extend the period during which such foods remain fresh or crisp.

It is a further object of my invention to provide a new and improved dehydrating compartment for use with refrigerator cabinets and the like.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 illustrates a refrigerator cabinet embodying the features of my invention and Fig. 2 is an enlarged sectional view taken along the lines 2—2 of Fig. 1.

Referring to the drawing, I have illustrated a refrigerator cabinet 10 of the domestic type having a food storage compartment 11 defined by suitable heat insulated walls and a closure member 12. The walls of the cabinet include an inner liner 13 and an outer casing or liner 14, the space therebetween being filled with a suitable thermal insulating material 15. In order to provide refrigeration for the compartment 11, I have provided an evaporator or cooling element 16 of any suitable type, illustrated in the drawing as being arranged in the upper portion of the refrigerated food storage compartment at one side thereof. Inasmuch as the refrigerating apparatus forms no part of my present invention, it is not believed necessary to show the complete refrigerating system. I have illustrated a plurality of shelves 17 suitably retained in the desired positions on the walls of the compartment 11 as by shelf supports 18. I have also illustrated a cold storage receptacle 19 suitably supported immediately below the cooling element 16.

In the illustrated form of my invention the refrigerating unit including the motor compres-

sor element is located at the rear of the lower portion of the cabinet (not shown). Toward the front of this portion of the cabinet there is provided a dehydrator compartment 20 in the form of a slideable drawer. In the illustrated form of my invention the dehydrator comprises a top or cover portion 21 having a downwardly and inwardly turned flange 22 extending longitudinally along each edge of the cover, the inwardly turned portion of the flange serving as a supporting rail for the outwardly turned flange 23 of the slideable container 20. The cover 21 may be supported from the cabinet in any desired manner as by brackets 24 suitably secured as by welding to the cover and the cabinet frame.

The dehydrator receptacle 20 should be substantially airtight in order to minimize the leakage of moisture-carrying air into the interior of the receptacle. Therefore, the flange 22 of the cover preferably extends around the sides and rear of the receptacle. In the illustrated form of my invention, the front wall of the receptacle 20 is in the form of a closure member or panel 25 contacting the outer surface of the lower portion of the refrigerator cabinet in the closed position thereof. A handle member 26 is provided to facilitate operation of the receptacle or drawer 20. The cover or panel portion 25 is provided with suitable sealing means (not shown) for sealing the space between the panel member 25 and the front of the refrigerator cabinet in order to minimize the possibility of the transfer of air and water vapor between the interior of the receptacle 20 and the air exteriorly of the cabinet through that space.

I have provided communication between the food storage compartment and the interior of the dehydrator compartment or receptacle in order to maintain a relatively low relative humidity in the dehydrator compartment.

When two air-tight compartments containing gases are interconnected, the gases become intermingled and the pressure of each gas in one compartment becomes equal to the pressure of the same gas in the other. If one compartment is maintained at a substantially different temperature than the other and one of the gases is water vapor, one compartment will have a different relative humidity than the other so long as vapor pressures remain constant. For example, if the temperature of the refrigerated compartment is approximately forty degrees F. and the relative humidity is about thirty per cent and the temperature of the dehydrator compartment is of the order of eighty degrees F.,

the latter compartment will have a relative humidity of approximately ten per cent. Thus, if the compartments are thermally insulated from each other and interconnected, a lower relative humidity will prevail in the warmer compartment.

In the illustrated form of my invention, this interconnecting or communicating means comprises a passage, such as a conduit 27, between the compartments. The conduit preferably is formed from relatively poor heat conducting material, as rubber, in order to minimize the flow of heat into the cooling compartment. The conduit is preferably disposed below the evaporator for a purpose to be described later.

In order to accelerate the equalization of vapor pressures in the compartments, I have provided a second passage, which may comprise a conduit 28 communicating between the compartments. I have illustrated a tubular conduit suitably retained in a vertically extending recess 29 in the inner liner 13. The conduit may be flattened, as shown, to provide a relatively smooth surface. However, any other suitable passage may be employed, if desired. Conduit 28 may be formed of any suitable material and may extend through the cabinet wall into the dehydrator compartment or that portion 30 extending through the wall may be separate but in any case the portion 30 preferably is a relatively good heat insulator. The upper end of the conduit 28 preferably opens into the upper end of the food storage compartment at a point remote from the evaporator or cooling element. The lower end should communicate with the dehydrator compartment at a point spaced from the conduit 27 a substantial distance.

As is well understood, the air cooled by the cooling element, being heavier than the air in remote sections of the cooled compartment, tends to fall and displaces the lighter warmer air. This movement creates a partial suction which tends to draw toward that region the warmer air in the upper portion of the compartment. Consequently, the warmer air is drawn across the evaporator and is cooled. The above-described disposition of conduits 27 and 28 makes use of this air circulation. A small amount of the cool air passes through the conduit 27 and displaces air and entrained water vapor upwardly through conduit 28.

As is well understood, moisture contained in the air within the refrigerated compartment condenses out and is deposited on the coldest portion of the compartment, that is, the cooling element or evaporator, appearing thereon in the form of frost. The provision of the conduits between the compartment makes it possible to utilize this action to dehydrate the air in the receptacle 20 because the moisture-containing air is forced out of the dehydrator and is replaced by the cooler dehydrated air entering the dehydrator. By making the conduits relatively small in cross section, the refrigeration in the receptacle or compartment 20 is substantially prevented and no substantial addition to the load on the refrigerating system results.

The equalization of pressures may further be accelerated by disposing the upper end of conduit 27 immediately below the evaporator.

Modifications will occur to those skilled in the art. For example, the dehydrator compartment or receptacle may be placed in any desired location. Also, while a sliding receptacle is illustrated, the dehydrator may be fixed as to position

and be equipped with a door in the front wall, for example.

While I have shown a particular embodiment of my invention, I do not desire my invention to be limited to the particular construction shown and described and I intend in the appended claims to cover all modifications within the spirit and scope of my invention.

What I claim as new and desire to secure by Letters Patent of the United States, is:

1. In a refrigerator having a refrigerated compartment and a cooling element disposed therein, a substantially air tight receptacle associated with said refrigerator cabinet, and means including a plurality of passages communicating between the interior of the compartment and the interior of the receptacle for permitting the passage of water vapor and air from the receptacle to the refrigerated compartment, said passages being sufficiently small in cross section to substantially prevent refrigeration of said receptacle.

2. In a refrigerator having a refrigerated compartment and a cooling element disposed therein, a substantially air-tight receptacle associated with said refrigerator cabinet, and means including a plurality of passages communicating between the interior of the compartment and the interior of the receptacle for permitting the passage of water vapor and air from the receptacle to the refrigerated compartment, the ends of said passages associated with said refrigerated compartment being spaced apart a substantial distance and the ends of the passages associated with the receptacle being spaced apart a substantial distance, said passages being sufficiently small in cross section to substantially prevent refrigeration of said receptacle.

3. In a refrigerator having a refrigerated compartment and a cooling element disposed therein, a substantially air-tight receptacle associated with said refrigerator cabinet, and means including a plurality of passages communicating between the interior of the compartment and the interior of the receptacle for permitting the passage of water vapor and air from the receptacle to the refrigerated compartment, one of said passages terminating in the lower portion of the refrigerated compartment, said passages being sufficiently small in cross section to substantially prevent refrigeration of said receptacle.

4. In a refrigerator having a refrigerated compartment and a cooling element disposed therein, a substantially air-tight receptacle associated with said refrigerator cabinet, and means including a plurality of passages communicating between the interior of the compartment and the interior of the receptacle for permitting the passage of water vapor and air from the receptacle to the refrigerated compartment, one of said passages terminating immediately below said cooling element, said passages being sufficiently small in cross section to substantially prevent refrigeration of said receptacle.

5. In a refrigerator having a refrigerated compartment and a cooling element disposed therein, a substantially air-tight receptacle associated with said refrigerator cabinet, and means including a plurality of passages communicating between the interior of the compartment and the interior of the receptacle for permitting the passage of water vapor and air from the receptacle to the refrigerated compartment, the ends of said passages associated with said refrigerated compartment being spaced apart a substantial distance and the ends of the passages associated

with the receptacle being spaced apart a substantial distance, one of said passages terminating in said refrigerated compartment below said cooling element, said passages being sufficiently small in cross section to substantially prevent refrigeration of said receptacle.

6. In a refrigerator having a refrigerated compartment and a cooling element disposed therein, a substantially air-tight receptacle associated with said refrigerator cabinet, and means including a plurality of passages communicating between the interior of the compartment and the interior of the receptacle for permitting the passage of water vapor and air from the receptacle to the refrigerated compartment, one of said passages communicating with the refrigerated compartment below said cooling element and the other of said passages communicating with the upper portion of said refrigerated compartment.

7. In a refrigerator having a refrigerated compartment and a cooling element disposed therein, a substantially air-tight receptacle associated with said refrigerator cabinet, and means including a plurality of passages communicating between the interior of the compartment and the interior of the receptacle for permitting the passage of water vapor and air from the receptacle to the refrigerated compartment, one of said passages communicating with the refrigerated compartment below said cooling element and the other of said passages communicating with the upper portion of said refrigerated compartment at a point spaced from said cooling element.

8. In a refrigerator having a refrigerated com-

partment and a cooling element disposed therein, a substantially air-tight receptacle associated with said refrigerator cabinet, and means including a plurality of passages communicating between the interior of the compartment and the interior of the receptacle for permitting the passage of water vapor and air from the receptacle to the refrigerated compartment, one of said passages communicating with the lower portion of said refrigerated compartment below said cooling element and the other of said passages communicating with the upper portion of the refrigerated compartment at a point spaced from said cooling element.

15 9. In a refrigerator having a refrigerated compartment and a cooling element disposed therein, a substantially air-tight receptacle associated with said refrigerator cabinet, and means including a plurality of passages communicating between the interior of the compartment and the interior of the receptacle for permitting the passage of water vapor and air from the receptacle to the refrigerated compartment, the ends of said passages associated with the receptacle being spaced apart a substantial distance, one of said passages communicating with said refrigerated compartment below said cooling element and the other of said passages communicating with the upper portion of the refrigerated compartment at a point spaced from said cooling element, the ends of said passages associated with said refrigerated compartment being spaced apart a substantial distance.

ALBERT F. WILD.
